UNITED STATES PATENT OFFICE.

OSCAR W. RICHARDSON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WARP-STOP-MOTION-ASSEMBLING DEVICE.

1,372,312.

Specification of Letters Patent. Patented Mar. 22, 1921.

Application filed April 10, 1919. Serial No. 239,078.

To all whom it may concern:

Be it known that I, OSCAR W. RICHARDSON, a citizen of the United States, residing at Worcester, in the county of Worcester and State of Massachusetts, have invented a new and useful Warp-Stop-Motion-Assembling Device, of which the following is a specification.

This invention relates to a device for use in assembling certain parts of a warp stop motion of the type shown in the patent to Regan, No. 1,265,112 dated May 7, 1918, and also in the prior application of Holmes, Serial No. 248,268 filed August 5, 1918.

This patent and application show a form of stop motion in which the vibrator or detector bars commonly extend through openings in the upper ends of the drop wires. A change of weave or fabric frequently requires the placing of a new warp in a loom with an entire new application of drop wires thereto. The style of drop wire commonly used, has an open slot at its lower end, a wire being dropped over each warp thread after the warp is placed in the loom. It is thereafter necessary to insert the vibrator bars longitudinally through the openings in the upper ends of the drop wires. When this type of stop motion is applied to looms not especially designed to receive it, the loom side or other parts of the loom associated therewith frequently interfere with such insertion of the vibrator bars when the stop motion is in normal position.

It is the object of my present invention to provide means by which certain parts of the warp stop motion may be moved to a position permitting insertion of the vibrator bars and may be thereafter returned to normal position, at all times retaining said parts in definite relative positions.

In the preferred form, my invention comprises a support for the separator bars, for certain additional bars termed "stringer" bars, and for the vibrator bars. These supports are commonly used in pairs and provision is made for guiding them horizontally on the end frames of the stop motion from and toward the operative position of said stop motion parts.

My invention further relates to arrangements and combinations of parts hereinafter described and more particularly pointed out in the appended claims.

A preferred form of my invention is shown in the drawings, in which

Figure 1 is a side elevation of one of my improved assembling devices;

Fig. 2 is a rear elevation thereof in its initial position;

Fig. 3 shows the same parts in raised position;

Fig. 4 shows the assembling device moved sideways to coöperate with the guide formed on the end frame of the stop motion;

Figs. 5 and 6 are sectional views taken along the lines 5—5 and 6—6 in Fig. 1;

Fig. 7 shows the position of the stop motion relative to one type of loom side;

Fig. 8 shows the type of drop wire commonly used, and

Fig. 9 is a partial perspective view of the device.

The stop motion to which my invention particularly applies comprises end frames 10 suitably supported in fixed relation to the loom sides and providing a support for a plurality of separator or guide bars 11 which extend across the loom on each side of each bank of drop wires. These bars are held in normal position by lugs 12 (Figs. 1 and 2) and by a ledge 13, the lugs and ledge being separated to form a groove 14 for a purpose to be disclosed.

Each of my improved assembling devices, in its preferred form, comprises a body member 15 having a series of slots 16 opening upwardly and a second series of slots 17 open at their lower ends. Each member 15 is also provided with a projection or flange 18 at its lower edge adapted to enter the groove 14 above described. A cover plate 19 is pivoted at 20 to the body member 15, and a spring latch 21 holds the plate in closed position. The plate 19 is provided with a plurality of downwardly opening slots 22 adapted to receive the vibrator bars as hereinafter described. A cross pin 23 may be inserted in holes 24 in the member 15, and is then positioned transversely of the slots 17 and adjacent the lower ends of the slots 16.

A relative position of stop motion and loom side which is frequently encountered is indicated in Fig. 7, in which it will be seen that longitudinal insertion or removal of the vibrator bars 22^a is impossible.

When it is necessary to set up the stop motion with a new warp in such a loom, the

warp is placed in the loom and a wire W, such as is shown in Fig. 8, is dropped over each of the warp threads. Before the drop wires are inserted, however, one of my assembling devices is mounted at each end of the stop motion by swinging back the cover plate 19 and raising the body member 15 so that the separator bars 11 enter the slots 16, as shown in Fig. 2, and thereafter latching the cover plate. Each assembling device is then raised to the position shown in Fig. 3, thus lifting the separator bars above the lugs 12. The devices are then moved endwise until the flanges 18 enter the grooves 14. So-called "stringer" bars 25 are then temporarily inserted from below in the slots 17 and are held in position therein by inserting the cross pins 23. These stringer bars are used merely for temporarily alining the drop wires in each bank as they are placed upon the warp threads.

After the drop wires are all in place, the assembling devices are drawn rearward of the loom along the grooves 14 carrying the separator bars 11, the stringer bars 25 and the drop wires W to a rearward position permitting longitudinal insertion of the vibrator bars 22^a in the openings in the upper ends of the drop wires W. This position of the parts is best shown in Fig. 1.

After the vibrator bars are inserted, the stop motion parts may be returned to initial position by sliding the devices 15 forward along the grooves 14 (Fig. 4). It will be noted that the flanges 18 fit the grooves 14 so closely that the stop motion parts are firmly supported in every position of the parts.

While the vibrator bars 22^a are somewhat longer than the distance between the end frames 10 of the stop motion, it is easy to move one assembling device forward slightly ahead of the other device, thus permitting one end of each vibrator bar to be inserted in its supporting opening 26 and to be moved through the opening a sufficient distance to permit the other end to clear the opposite end frame 10. The stringer bars 25 are then removed, the cover plate 19 is swung back to release the vibrator bars, and the assembling devices are detached by successive sidewise and downward movements.

It will thus appear that I have provided assembling devices by which the essential longitudinally extending parts of the stop motion may be held in definite relative position while they are displaced rearwardly to permit insertion or removal of the vibrator bars.

Having thus described my invention, it

will be evident that changes and modifications can be made therein by those skilled in the art without departing from the spirit and scope of my invention as set forth in the claims, and I do not wish to be otherwise limited to the details disclosed, but what I claim is:—

1. A warp stop motion assembling device comprising supports to hold the longitudinally extended removable parts of a stop motion in definite relation to each other, and means to guide said supports and said parts rearwardly to inoperative position and forwardly to operative position and to support said parts in both positions. 70

2. A warp stop motion assembling device comprising positioning supports for the longitudinally extended removable parts of a warp stop motion, and means to guide said supports, said means comprising cooperating parts on said supports and said stop motion effective to guide said supports and said removable parts rearwardly to inoperative position and forwardly to operative position and to support said parts in both 80 positions. 85

3. An assembling device for a warp stop motion having end frame members comprising means to hold the longitudinally extended removable parts of a stop motion in relative position, said means coöperating with said end frame members to guide said parts rearwardly to inoperative position and forwardly to operative position while retaining a fixed relation of said parts to each other and being also effective to support said parts in both positions. 90 95

4. A warp stop motion assembling device comprising means to position separator bars, stringer bars and vibrator bars relative to each other, and means to guide said parts rearwardly to inoperative position and forwardly to operative position and to support said parts in both positions. 100

5. An assembling device for a warp stop motion having end frames comprising supports provided with a plurality of slots to receive separator bars, a plurality of inverted slots to receive stringer bars, and a plurality of openings to receive vibrator 105 bars, and means to hold the stringer bars in said inverted slots, said supports being slideable on said end frames to guide said bars collectively to inoperative and operative positions and to support said parts in both 110 115 positions.

In testimony whereof I have hereunto affixed my signature.

OSCAR W. RICHARDSON.
